UNITED STATES PATENT OFFICE.

LARKIN STOWE, OF PLEASANT VIEW, KENTUCKY.

DISPENSING-RECEPTACLE.

979,592.

Specification of Letters Patent. Patented Dec. 27, 1910.

Application filed January 3, 1910. Serial No. 536,031.

To all whom it may concern:

Be it known that I, LARKIN STOWE, a citizen of the United States, residing at Pleasant View, in the county of Whitley and State of Kentucky, have invented a new and useful Improvement in Dispensing - Receptacles, of which the following is a specification, reference being had to the accompanying drawing.

10 My improvement relates particularly to a device which is to constitute a detachable or removable spout and cover for the discharge opening or port of dispensing receptacles.

15 The improvement is specially designed for use on metallic cans containing blasting powder, such cans being used by miners to fill smaller receptacles or cartridges, from time to time.

20 In the accompanying drawings, Figure 1 is a plan illustrating my improvement applied to the discharge opening or port in the head of the powder can; Fig. 2 is a bottom view of my apparatus; Fig. 3 is a section through said device and the adjacent 25 portion of the head of the powder can; Fig. 4 is a similar section showing a funnel combined with the other members of the device.

Powder cans used for handling blasting powder in bulk are usually formed of sheet 30 metal and with flat ends or heads, one of said ends having a port or discharge opening through which the powder is discharged and a flat gate being provided for covering said port. It is desirable, almost essential, that the ends of such cans be flat, in order that 35 the cans may be set on their ends and upon each other. My improved device is applied to said port after the removal of said gate.

40 In the drawings, 1 is a part of a can end or head and 2 is the usual circular port. Upon said end is set the tubular spout, 3, having at its base a lateral flange, 4, which is extended at one point to form a horizontal tongue, 5. The inner base diameter of said 45 spout is preferably the same as the diameter of said port. To the inner face of the base portion of the wall of the spout is applied a metal strip, 6, which extends below said base and thence laterally and outward to form a 50 tongue, 7, far enough below the flange, 4, to allow the end wall, 1, of the can to extend between said flange and said tongue. Upon the end wall, 1, is secured a plate, 8, having a bent over ear, 8', which is directed toward 55 the port, 2, and is far enough above said

plate to extend over and bind upon the tongue, 5.

When the spout is to be attached, it is placed over the port, 2, inclined sufficiently to allow the tongue, 7, to enter the port. 60 Then the spout is brought into the upright position directly over the port and rotated sufficiently to wedge the tongue, 5, beneath the ear, 8', whereby the spout becomes firmly secured. A cap, 9, fits removably over the 65 upper end of said spout and serves to close the port, 2, excepting when powder is to be poured from the can. At such times, said cap is removed, and the can tilted and the spout directed into the receptacle which is 70 to receive the charge of powder. The pouring of powder from said spout into another receptacle having a relatively small mouth may be facilitated by the use of a funnel, 10, such as is shown in Fig. 4, said funnel 75 being a tapering tube adapted to have its larger end fit around the spout, 3, and to have its smaller end receive the cap, 9, when no powder is being taken from the can, this manner of disposing of said funnel during 80 non-use being adopted for the purpose of providing a secure and definite place for stowing the funnel.

Ordinary explosive powder cans now in use have two ears, 8', the same being located 85 at opposite sides of the port to receive a heretofore-used disk-form gate for closing said port. Hence my improved spout and closing device is adapted for use upon said cans without modification of the latter. 90 Thus, for the marketing of my improvement, it is necessary to manufacture only two small sheet metal parts, if the funnel, 10, is not used; or three such parts, if said funnel is to be used. 95

I claim as my invention:

1. In a device of the nature described, the combination of a spout adapted to seat around a port in the wall of a receptacle and having a tongue adapted to enter said 100 port and extend beneath said wall and having another tongue located opposite the first-mentioned tongue and adapted to extend into engagement with a member located upon the outer side of said wall adjacent 105 said port.

2. In a device of the nature described, the combination of a cap and a spout, said cap being adapted to seat upon said spout and said spout being adapted to seat around a 110

port in the wall of a receptacle and having a tongue adapted to enter said port and extend beneath said wall and having another tongue located opposite the first mentioned 5 tongue and adapted to extend into engagement with a member located upon the outer side of said wall adjacent said port.

3. In a device of the nature described, the combination of a spout, a funnel, and a cap, 10 said funnel being adapted to seat upon said spout and said cap being adapted to seat upon said funnel, and said spout being adapted to seat around a port in the wall of a receptacle and having a tongue adapted 15 to enter said port and extend beneath said wall and having another tongue located opposite the first-mentioned tongue and adapted to extend into engagement with a member located upon the outer side of said wall 20 adjacent said port.

4. In a device of the nature described, the combination of a spout adapted to seat around a port in the wall of a receptacle and having a flange around its base and having 25 a tongue adapted to enter said port and extend beneath said wall and having another tongue located opposite the first-mentioned tongue and adapted to extend into engagement with a member located upon the outer 30 side of said wall adjacent said port.

5. In a device of the nature described, the combination of a cap and a spout, said cap

being adapted to seat upon said spout and said spout being adapted to seat around a port in the wall of a receptacle and having 35 a flange at its base and having a tongue adapted to enter said port and extend beneath said wall and having another tongue located opposite the first-mentioned tongue and adapted to extend into engagement with 40 a member located upon the outer side of said wall adjacent said port.

6. In a device of the nature described, the combination of a cap, a funnel, and a spout, 45 said funnel being adapted to seat upon said spout and said cap being adapted to seat upon said funnel, and said spout being adapted to seat around a port in the wall of a receptacle and having a flange at its base and having a tongue adapted to enter said 50 port and extend beneath said wall and having another tongue located opposite the first-mentioned tongue and adapted to extend into engagement with a member located upon the outer side of said wall adjacent 55 said port.

In testimony whereof I have signed my name, in presence of two witnesses, this twenty second day of December, in the year one thousand nine hundred and nine.

LARKIN STOWE.
